UNITED STATES PATENT OFFICE.

GEORGE A. JOHNSON, OF CHICAGO, ILLINOIS, ASSIGNOR TO WILLIAM H. MINER, OF CHICAGO, ILLINOIS.

DRAFT-RIGGING FOR RAILWAY-CARS.

1,139,875.

Specification of Letters Patent.

Patented May 18, 1915.

Application filed May 24, 1913, Serial No. 769,574. Renewed April 5, 1915. Serial No. 19,347.

To all whom it may concern:

Be it known that I, GEORGE A. JOHNSON, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging in which the compression resisting members are of high capacity in buffing movement, and of an easier action in pulling movement.

In the drawings forming a part of this specification Figure 1 is a side elevation partly in vertical longitudinal section on line 1—1 of Fig. 2 of a draft rigging embodying my invention. Fig. 2 is a plan view partly in horizontal section on line 2—2 of Fig. 1. Fig. 3 is a plan view partly in horizontal section illustrating the position of the parts when under full compression in pulling movement of the draft rigging. Fig. 4 is a plan view partly in horizontal section illustrating the position of the parts when under full compression in buffing movement of the draft rigging.

Referring to the drawings 5, 5 represent draft sills or parts of the car frame to which the draft rigging is applied, 6 the end sill, 7 the buffer block, 8 the draw bar carry iron, 9 the tie plate, 10, 10 the front stop members having the stop shoulders 11, 11, 12 the rear stop member, 13 the draw bar, 14 the draft gear, 15 the draft yoke. The draft yoke is forwardly provided with a hollow member 16 having an opening 17 to receive the draw bar, the said member 16 being provided with the lateral slots 18 to receive the coupler key 19 which passes through the draw bar, and also in preferable construction through slots 20, 20 in the front stop members and adjacent portions of the draft members. The slots 20, 20 and 50 the slot 18 and the member 16 are suitably longitudinally extended to permit the rearward movement of the draw bar against the draft gear 14, which is suitably mounted within the draft yoke 15. The draft yoke 15 is provided at its rear end with a longitudi-

nal opening 21 extending through the rear member 22, which connects the limbs 23, 23 of the draft yoke. The draft gear 14 comprises a shell 24 closed at its forward end by the preferably integral plate 25, said plate 60 having the lateral extensions 26, 26 at either side of the shell, which extensions are adapted to engage against the front stop shoulders 11, 11 in normal position and on forward movement of the draw bar.

Within the shell is mounted the spring mechanism 27 and the friction mechanism 28 in engagement therein, the spring mechanism 27 preferably comprising an outer spring 29 and an inner spring 30 nested 70 therein, the said springs being seated at their forward end against the friction shell and at their rear end against the friction mechanism. The friction mechanism comprises the friction shoes 31, the wedge 32, 75 and in preferable construction the antifriction rolls 33. The friction shoes 31 are preferably three in number, each having an outer friction face 34 adapted to engage the internal friction face 35 of the shell, and each 80 having an inner wedging face 36 preferably provided with an antifriction roll seat 37 to receive one of the antifriction rollers 33. The wedge 32 is a block like member provided with a plurality of wedging faces 38, 85 there being one for each friction shoe. One of the antifriction rolls 33 is seated between each wedging face of the wedge and the adjacent inner wedging face of the friction shoe. The wedge 32 has a rearward projection 39 which passes through the opening 21 in the member 22 of the draft yoke 15, and engages at its rear face 40 in normal position of the gear, as illustrated in Fig. 1 of the drawings, and in buffing movement 95 thereof, as illustrated in Fig. 4 of the drawings, the rear stop member 12. The said wedge 32 is provided with a rearwardly opening recess 41 to receive the head 42 of a connecting rod 43, which passes through a 100 longitudinal perforation 44 in said wedge and extends forwardly through the shell and the forward end thereof, where it is provided with a nut 45 which is received within a recess 46 in the outer forward end 105 of said shell.

The rear stop member 12 is preferably a one-pieced structure secured between the draft members, and is provided with the inwardly extended limiting stop shoulders 47, 110

47 at either side thereof. The rear end of the shell is adapted to engage against said limiting stop shoulders on rearward movement, and through such engagement the further compression of the compression resisting parts of the draft gear is limited. The said stop member 12 is also provided with a stop shoulder 48, preferably comprising the transverse wall 49 and the preferably integral reinforcing web 50 back of the same, the said stop shoulder 48 being engaged by the wedge 32 in the normal position of the draft gear and in rearward movement thereof. In front of the stop shoulder 48 the stop member 12 is provided with a space 51 within which the rear end of the draft yoke 15 is adapted to be received on rearward movement of the shell.

The rear ends of the friction shoes 31 engage against the inner face 52 of the rear connecting member 22 of the draft yoke. On forward movement of the draw bar the draft yoke is drawn forwardly by means of the coupler key 19, and the friction shoes 31 are drawn within the shell by the forward movement of the draft yoke, the said shell being in engagement at its forward end against the front stop member, and through said forward movement of the friction shoes the spring mechanism 27 is compressed between the forward end of the shell and the said friction shoes. On such movement it will be apparent that the wedge 32 does not spread the friction shoes or operate against the same.

An easy start may be given cars to which this draft rigging is applied by reason of the fact that in pulling movement of the draw bar the compression resisting members 40 of the draft gear in operation are the springs. On release movement the sudden recoil of the spring is prevented by reason of the fact that its rearward movement is somewhat retarded by the drag of the friction shoes against the shell. On rearward movement of the draw bar the coupler key slides within the slots 18 in the member 16 of the draft yoke, and the draw bar forces the shell rearwardly, the wedge is stopped 50 against the rear stop member, and as the shell moves rearwardly the wedge spreads the friction shoes into frictional engagement with the shell, the springs meanwhile are compressed until the rearward travel of the shell is limited as it comes into engagement with the limiting stop shoulders 47 of the rear stop member 12. In rearward or buffing movement of the draw bar both the friction and spring members within the shell 60 are in compression resisting action.

I claim:—

1. In a draft rigging for railway cars, in combination, a draw bar, a draft yoke, front and rear stop members, a shell, springs, friction shoes and wedge within the shell, the

said draft yoke being in engagement with the friction shoes, the wedge passing through said yoke and adapted to spread the friction shoes only on rearward movement of the draw bar.

2. In a draft rigging for railway cars, the combination of stop members and draft yoke with a draft gear, the draft gear comprising a shell having a rearward opening, friction shoes, springs and wedge within the shell, the springs being seated between the shell and friction shoes, the wedge engaging the rear stop member, said wedge being adapted to spread the friction shoes only on rearward movement of the shell.

3. In a draft rigging for railway cars, in combination, a draft yoke, stop members, a rearwardly opening shell, springs and friction shoes within the shell, a wedge interposed between the friction shoes and rear stop member, the forward movement of the yoke compressing the springs without spreading the friction shoes, and the rearward movement of the shell compressing the springs and forcing the friction shoes into spreading engagement with the wedge.

4. In a draft rigging for railway cars, in combination, a draw bar, draft yoke, stop members, a rearwardly opening shell, springs, friction shoes within the shell, a wedge interposed between the friction shoes and rear stop members, the draft yoke being in engagement with the friction shoes and provided with an opening for the passage of the wedge.

5. In a draft rigging for railway cars, in combination, stop members, a draw bar, shell and means for connecting the same, of spring mechanism and friction mechanism within the shell, the friction mechanism including a wedge adapted to directly engage the rear stop member, and to spread the friction mechanism only on rearward movement of the draw bar.

6. In a draft rigging for railway cars, a draft gear comprising a shell, springs, friction shoes and a wedge within the shell, in combination with a draw bar, draft yoke and stop members, the wedge being seated against the rear stop member on rearward movement of the draw bar, and in such movement adapted to spread the friction shoes, the yoke being in engagement with the friction shoes on forward movement of the draw bar.

7. In a draft rigging for railway cars, in combination, a draw bar, a draft yoke connected thereto, front and rear stop members, a shell, friction shoes, springs and wedge within the shell, the draft yoke being in engagement with the friction shoes, and adapted to compress the springs between said shoes and the shell on forward movement of the draw bar, the said yoke having an opening for the passage of the wedge, the wedge

engaging the rear stop member and spreading the friction shoes only on rearward movement of the draw bar.

8. In a draft rigging for railway cars, in combination, draft members, front and rear stops between said draft members, a draw bar, a yoke connected thereto, a shell within said yoke, springs, friction shoes and wedge within the shell, the draft yoke engaging the friction shoes, and the wedge being in operative engagement between the rear stop member and friction shoes only on rearward movement of the shell.

9. In a draft rigging for railway cars, in combination, a draft bar, stop members, a shell having a rearward opening, springs, friction shoes and wedge within the shell, means connecting the draw bar and friction shoes adapted to compress the springs on forward movement of the draw bar without wedging engagement between the friction shoes and the wedge.

10. In a draft rigging for railway cars, in combination, a draw bar, stop members, a shell, springs, friction shoes and wedge within the shell, a yoke connecting the draw bar and friction shoes, the wedge being seated independently of said yoke and

adapted to spread the friction shoes only on rearward movement of the shell.

11. In a draft rigging for railway cars, in combination, front and rear stop members, a draw bar, draft yoke, friction shell, springs, friction shoes and wedge within the shell, the draft yoke engaging the friction shoes, the wedge passing through said yoke and being in spreading engagement with the friction shoes only on rearward movement of the shell, the rear stop member being provided with shoulders to engage the shell in its rearward movement, and limit the compression of the parts within the shell.

12. In a draft rigging for railway cars, the combination of stop members and a draft yoke with a draft gear, the draft gear comprising a shell having a rearward opening, springs, friction shoes and wedge within the shell, the draft yoke directly engaging the friction shoes and the wedge directly engaging the rear stop member, the wedge being adapted to spread the friction shoes only on rearward movement of the shell.
